UNITED STATES PATENT OFFICE.

BARNARD B. SAVAGE, OF NEW HAVEN, CONNECTICUT.

HAMMOCK.

1,056,947.

Specification of Letters Patent.

Patented Mar. 25, 1913.

Application filed January 26, 1912. Serial No. 673,515.

To all whom it may concern:

Be it known that I, BARNARD B. SAVAGE, a citizen of the United States, residing at New Haven, in the county of New Haven and State of Connecticut, have invented certain new and useful Improvements in Hammocks, of which the following is a specification, reference being had therein to the accompanying drawings.

10 My invention relates to new and useful improvements in hammocks, referring particularly to that type known as a ship's hammock, and has for its object, among other things, to provide means, whereby the cushion may be entirely covered when desired, so as to keep the same dry and without resorting to the usual means of raising the entire hammock to a point above the normal level of the cushion. This latter operation 15 is usually accomplished by a rope or a block and falls, both of which are cumbersome to operate and unsightly in appearance.

To these, and other ends, my invention consists in the hammock, having certain 25 details of construction and combinations of parts, as will be hereinafter described, and more particularly pointed out in the claims.

Referring to the drawings, in which like 30 numerals of reference designate like parts in the several figures: Figure 1 is a view of my improved hammock complete; Fig. 2 is an enlarged sectional view thereof upon line A—B of Fig. 1; and Fig. 3 is a similar view 35 upon line C—D of Fig. 1.

My invention is preferably applied to a ship's hammock of the ordinary construction, wherein the frame 1, supporting a cushion 2 is suspended by a canvas 3, the 40 opposite ends thereof, having cords or chains 4 therein, which are joined to the suspension rings 5. That portion of the canvas 3 that is at right angles to the cushion 2, is known as the suspension end, and 45 is herein designated by the numeral 6. Secured upon the inside of the suspension end portion, at the bottom 8 thereof, is the supplemental end strip 7, that is attached to the suspension end 6 at its upper end by a plurality 50 of separable fastening devices 9. This supplemental end strip, when in its up or open position, as shown in Figs. 1 and 3 of the drawings, constitutes a convenient receptacle for magazines or papers, generally 55 described as a magazine rack. To provide such rack, the supplemental end strips are

of less height than the suspension ends for a portion of their widths, as clearly shown in Fig. 1, the rear extension of the supplemental end strip being maintained in the 60 vertical position in contact with the suspension end 6 as shown in Fig. 1 when desirable by any ordinary means, as a snap button or the like, not shown in the drawings.

Upon the rear side of the cushion, and secured thereto at its lower end, is the wind shield 10, within which is inserted the rod 11, and the flap portion 12, beyond the rod 11, is provided near its outer edge with a plurality of fastening devices 13. The wind 65 shield is secured at each end to the suspension end portions 6 by one or more fastening devices 14. When in its up position, as shown in the drawings, the rod 11 is adjacent to the top of the suspension end portions 70 6, and the flap 12 is lying loose upon the outside thereof. The rod 11 is designed to prevent the sagging of the wind shield, and is 75 only of sufficient strength to accomplish this result.

It is desirable and convenient sometimes 80 to make the wind shield and the supplemental end strip 7 of a single piece of material, as shown in the drawings, but the supplemental end strips may be made separate 85 if desired and secured to the wind shield, either by stitching or by means of fastening devices.

I have not shown in detail the particular 90 type of fastening device that is used with my invention, as it is no part thereof, and because any one of many different types of fastening devices may be used equally as well.

In the drawings the hammock is shown when in its position ready for use, with the wind shield and supplemental end strips up and the cushion uncovered. To cover the cushion and prevent the same from being wet, either in a storm or at night by the dews, the supplemental end strips 7 are first unfastened at their upper ends and folded down onto the top of the cushion, as shown by the broken lines in Fig. 3, after which the wind shield is unfastened at its ends from the suspension end portions 6, and folded over the top of the cushion and the supplemental end strips 7, and secured by the engagement of the fasteners 13 upon the flap 12 with the fasteners 15, in which position all of the parts are covered and the wind shield and flap occupy the position in

relation to the cushion, shown by the broken lines in Fig. 2. By having the supplemental end strips 7 connected with the ends of the wind shield, it is impossible to turn down 5 the wind shield without at the same time turning down the supplemental end strips, so that the same will not be left in their up position through inadvertence or mistake. The water that strikes the top of the wind 10 shield when in its down position is shed therefrom on either side thereof, and such water as is shed toward the ends, strikes the suspension end portion 6 upon the inside thereof, runs down between the supplemental end strip 7 and the suspension end 6, and escapes from the pocket therein through the plurality of gromets 16, secured in the suspension end portion 6 adjacent to the bottom thereof (see Fig. 3).

20 There are minor changes and alterations that can be made within my invention, and I would therefore have it understood that I do not limit myself to the exact construction herein shown and described, but claim all 25 that falls fairly within the spirit and scope of my invention.

Having described my invention, what I claim as new, and desire to secure by Letters Patent, is:—

30 1. A hammock including a seating, suspension ends attached thereto, supplemental end strips secured to the suspension ends, and a wind shield secured to said seating, said supplemental end strips and wind shield being adapted to be folded down upon the seating to cover the latter.

35 2. A hammock including a seating, sus-

pension ends attached thereto, supplemental end strips secured to the suspension ends, and a wind shield secured to said seating, 40 said supplemental end strips and wind shield being adapted to be folded down upon the seating to cover the latter, a flap portion projecting from the wind shield, and coöperating fastening devices carried by said flap 45 and seating.

3. A hammock including a seating, suspension ends attached thereto, supplemental end strips secured to the suspension ends, and a wind shield secured to said seating, 50 said supplemental end strips and wind shield being adapted to be folded down upon the seating to cover the latter, the suspension ends being formed with outlet openings immediately above the juncture of the supplemental end strips therewith.

4. A hammock including a seating, suspension ends attached thereto, supplemental end strips secured to the suspension ends, and a wind shield secured to said seating, 60 said supplemental end strips and wind shield being adapted to be folded down upon the seating to cover the latter, means for removably securing the wind shield to the suspension ends, and means for removably securing the upper ends of the supplemental end strips to the suspension ends.

In testimony whereof I affix my signature in presence of two witnesses.

BARNARD B. SAVAGE.
